CHARLES DE BERGUE, OF WESTMINSTER, GREAT BRITAIN.

Letters Patent No. 83,138, dated October 20, 1868.

IMPROVED TRACK-LIFTER.

The Schedule referred to in these Letters Patent and making part of the same.

To all whom it may concern:

Be it known that I, CHARLES DE BERGUE, of 10 Strand, in the city of Westminster, and Kingdom of Great Britain, engineer, have invented a certain new and useful "Improved Instrument for Use in Packing Permanent Way," and I do hereby declare that the following is a full and exact description thereof, reference being had to the accompanying drawings, forming part of this specification.

My invention has reference to raising the rails or rails and sleepers or permanent way of railways, for the purpose of packing it up and adjusting it to the desired level, in a more convenient manner than by the ordinary single-lever bar, which usually or frequently requires the combined efforts of four or five men to attain sufficient power, who have to retain it in position while the packing is being effected; and the invention consists of a mechanical instrument or contrivance involving the use of two members, with the ends, one of each, hinged or coupled together at one end of the instrument, one of such members being intended to take its bearing upon the ballast or ground, and the other to separate or become forced up away from the first by screw-power applied at the end of the instrument away from the coupling, and to lift with it the rail or rails and sleepers or permanent way to or beneath which it is applied, and to remain so lifted or separated without the aid or attention of any of the men employed. By these means the action or movement may be slow, but may be effected by one person, or if not so in certain cases, still, by fewer persons than are required by the present system.

The accompanying drawing further illustrates the manner of performing the invention, by representation of the improved instrument or contrivance.

Figure 1 is a plan view,

Figure 2 a longitudinal section, and

Figure 3 a transverse section through the screw-end of the instrument.

In these figures, *a* is a metal bed-plate, forming not only the lower member of the instrument, but also a frame or support for the other parts. *b* is the upper member, formed of wrought-iron, cast-steel, or malleable cast-iron, and lying within the recessed or hollow

form of the lower member when in the position shown, and hinged to same at the end marked *c*. The opposite end, *d*, is tapped with screwed hole for receiving the lifting-screw *e*, (not shown in fig. 1,) the lower end of which rests upon a properly-formed seating for it, cast in the member *a*. Upon this end of the screw, and upon the hinge or coupling at *c*, the weight of the jaw *b*, and any load it may carry, is supported. The member *a* is cast with a curved lip or rim, *a'*, which serves as a protection from the ballast falling into the recess, and also as a stop against the rail. *f* is an ordinary movable key or spanner, fitting on to upper end of the screw.

Figure 4 shows handle of same.

In using the instrument, a portion of the ballast is, if necessary, to be excavated between the sleepers, and the instrument so placed in or on the ballast under the rail *g*, that the rail may rest on or be immediately over the seats formed for it at *a'*, on the upper surfaces of the sides of the member *a*, and which seats may be fashioned differently, according to the form of rail. By turning the screw, the end *d* of the member *b* will be lifted, and the weight of rail and sleepers and appendages being supported on the said member, will be raised from off the seats *a'*, great power being obtained by the screw-action and the leverage. Moreover, it will remain so raised till lowered by reverse movement of the screw, and meanwhile the packing of the ballast may be effected without attention to the instrument itself. The handles *a''* serve for placing, removing, and carrying the instrument, the weight of which is not more than can be managed by one workman only, if desired.

Having thus fully described my invention,

I claim as new, and desire to secure by Letters Patent—

The within-described instrument, consisting of the metal bed-plate *a*, pivoted lever *b*, and operating-screw *e*, the whole constructed and operating substantially as and for the purpose herein set forth.

C. DE BERGUE.
